UNITED STATES PATENT OFFICE.

CHARLES H. ANDRUS AND CHARLES A. PLANK, OF HARRISBURG, PENNSYLVANIA.

DUMPING-CAR.

1,207,122.

Specification of Letters Patent.

Patented Dec. 5, 1916.

Application filed February 1, 1916. Serial No. 75,526.

To all whom it may concern:

Be it known that we, CHARLES H. ANDRUS and CHARLES A. PLANK, citizens of the United States, and residents of Harrisburg, in the county of Dauphin and State of Pennsylvania, have invented certain new and useful Improvements in Dumping-Cars; and we do hereby declare the following to be a full, clear, and exact description of the invention such as will enable others skilled in the art to which it appertains to make and use the same.

This invention relates to improvements in dumping cars and more particularly to doors for cars of the hopper type and operating means for such doors,—one object being to so construct and arrange the doors or outlet gates as to avoid possibility of leakage of material from the hopper body when said doors are closed.

A further object is to so construct and mount the doors or gates that the same may be easily operated, and to provide simple and efficient means for operating and controlling the doors or gates.

With these and other objects in view, the invention consists in certain novel features of construction and combinations of parts as hereinafter set forth and pointed out in the claims.

In the accompanying drawings; Figure 1 is a side elevation of a portion of a hopper car showing the application of our improvements; Fig. 2 is a transverse sectional view, and Fig. 3 is a sectional view on the line 3—3 of Fig. 1.

1 represents the car body, and 2 the center girder. The body 1 is of the hopper type, having sloping end walls or floors 3, 3, and 40 is divided centrally by a transverse hood 4 so that communicating hoppers 5—5 are formed at respective sides of the transverse center of the car. These hoppers are divided in their lower portions by means of hoods 45 6^a, 6^a, disposed over the center girder. At respective sides of the center girder, the inclined end floors 3 are extended to form the bottom walls of inclined chutes 6, the side walls of each of which are made with curved 50 free edges. Four inclined chutes 6 are thus provided, two at each side of the transverse center of the car and the chutes of the respective pairs being disposed to downwardly discharge toward each other and beneath 55 the transverse hood 4.

Plates 7, 7, (having a general triangular

shape) are securely riveted to respective sides of each chute and these plates may be connected by an integral plate member 8 lying against the bottom of the chutes,—the 60 plates 7—8 thus forming a hood which partially incloses the chute.

The plates 7 are made with curved free edges which conform to the curvature of the free edges of the side walls of the chute, and 65 said free edges of the plates are made with laterally projecting curved flanges 9. The upper portions of the plates 7 are offset, as at 10, to permit the attachment thereto of pivot bolts 11, and the side walls of the chute 70 may be made with holes 12 to facilitate the securing of said bolts. The bolts 11, constitute pivotal supports for brackets 12^a to which doors or gates 13 are secured. Each bracket 12^a is curved at its free edge and provided with a curved flange 14. Each door or 75 gate 13 is made convex or curved outwardly to conform to the similar curvature of the free edges of the sides of the chute, and is secured at its respective ends to the curved 80 flanges of two of the brackets 12^a. These brackets are made with grooves 14^a which receive the flanges 9 of the plates 7 at respective sides of a discharge chute 6, so as to prevent possibility of leakage of material past 85 the edges of the door or gate when the same is closed, and also to form guiding means for the door or gate when the same is being opened or closed. To further guard against leakage of material, each gate is provided 90 at its lower edge with a flange 15 which, when the gate is closed, engages the connecting plate 8 on the chute.

Brackets 16, depend from the sides of the car body and a bracket 17, depends from 95 the center girder centrally between the sides of the car. These brackets afford bearings for four transverse shafts, 18 and 22, located under the hood 4. Each shaft 18 is provided with two pairs of arms 19, the 100 pairs of arms on one shaft 18 being connected by rods 20, with the doors or gates for the chutes at one side of the central hood 4, and the pairs of arms 19 on the other shaft being similarly connected with 105 the doors or gates of the chutes at the other side of said central hood. Each shaft 18 may be provided with a gear 21 to receive motion from a pinion 23 on shaft 22, and a crank 24, may be connected with each pinion or to each shaft 22 for operating the same. Locking dogs 25 and 26 may be pro-

vided for locking the gears and thus securing the doors or gates securely locked when closed.

Our improvements afford simple and efficient means for controlling the discharge of material from a hopper car; the doors or gates are so curved outwardly as to operate easily against the pressure of the load, and the construction is such as to avoid possibility of leakage past the doors when the car is subjected to jolting and vibration when in transit.

Various slight changes might be made in the details of construction of our invention without departing from the spirit thereof or limiting its scope and hence we do not wish to restrict ourselves to the precise details herein set forth.

Having fully described our invention what we claim as new and desire to secure by Letters-Patent, is:—

1. The combination with a car body and a chute depending therefrom and having an outwardly curved outer end, of an outwardly curved convex sliding gate for closing the outlet end of the chute, pivoted brackets carrying said gate, said brackets being curved to conform to the curved outlet end of the chute and having grooves near their connection with the gate, and said chute provided with curved flanges entering said grooves.

2. The combination with a hopper body provided with an outlet chute at its bottom, said chute having a curved outlet end, of plates secured to the sides of said chute,

brackets pivoted to said plates and having curved lower edges, said gate secured to said brackets and connecting the same, said brackets having grooves near their free curved edges, and said plates having curved flanges to enter and move in said grooves.

3. The combination with a hopper body and an inclined chute depending therefrom, of plates secured to the sides of the chute, brackets pivoted to said plates and having convex free ends, said convex portions of the brackets having grooves, a convex gate secured to the convex portions of said brackets, and curved flanges projecting from said plates and entering the grooves in the curved free ends of said brackets.

4. The combination with a hopper body having an outlet chute, the latter provided with a curved outlet end, of an outwardly curved convex sliding gate for said chute, said gate and chute provided with intermeshing portions having sliding connection with each other, an operating shaft, arms on said shaft, rods connecting said arms with the gate at respective ends of the latter, and means for manually actuating said operating shaft.

In testimony whereof, we have signed this specification in the presence of two subscribing witnesses.

CHARLES H. ANDRUS.
CHARLES A. PLANK.
